UNITED STATES PATENT OFFICE.

ALFRED G. STEER, OF LANSDOWNE, PENNSYLVANIA, ASSIGNOR TO DAIRYMEN'S SUPPLY CO., OF LANSDOWNE, PENNSYLVANIA, A CORPORATION OF PENNSYLVANIA.

BOTTLE RINSING AND STERILIZING APPARATUS.

1,030,139.

Specification of Letters Patent. Patented June 18, 1912.

Application filed May 26, 1911. Serial No. 629,650.

To all whom it may concern:

Be it known that I, ALFRED G. STEER, a citizen of the United States, and a resident of Lansdowne, Delaware county, Pennsylvania, have invented certain Improvements in Bottle Rinsing and Sterilizing Apparatus, of which the following is a specification.

My invention relates to cleansing devices for bottles, and consists of an apparatus especially designed for use in the cleansing of milk bottles wherein hot water, preferably under steam pressure, is forced into the bottles, thoroughly washing and rinsing the same, and when such rinsing operation is complete, live steam is forced into the bottles for the purpose of effecting a complete sterilization of the same. This operation of rinsing and sterilizing the bottles follows a preliminary soak in a bath of cleansing liquid and a scrubbing of the interior of the bottles effected by a brush or other suitable means. These and other features of my invention are more fully described hereinafter, reference being had to the accompanying drawings, in which:

Figure 1, is a sectional elevation of apparatus embodying my invention; Fig. 2, is an end elevation of the same, looking in the direction of the arrow *x*, Fig. 1; Fig. 3, is an end elevation, looking in the direction of the arrow *y*, Fig. 1; Fig. 4, is a diagrammatic view illustrating the piping for the steam and hot water, and Figs. 5, 6, 7, 8, 9 and 10, are views illustrating details of my invention.

In the drawings herewith, 1 represents a suitable tank for hot water, in which a coil or elongated section of pipe with return bends, indicated at 2, is disposed. This hot water may be initially heated by live steam delivered from a pipe 3, connected to a main steam pipe 4, leading from a suitable source of supply, boiler or the like. The brush employed for the scrubbing operation may be driven by a steam turbine and when such apparatus is employed the exhaust steam therefrom may discharge into the tank of water to heat the same. After the apparatus is in operation, however, the steam employed to force the water into the bottles will maintain the desired heat therefor.

Above the tank, or at a point convenient thereto, a suitable guideway may be pro-

vided formed of rails 5, for the introduction of a case 6^a carrying a series of bottles disposed in an inverted position, and in the structure I have devised it is quite possible and practicable to wash twenty pints or a dozen quarts at a single time; the cases being capable of containing either number. The bottles may be supported by suitable racks or trays 6 having rings or collars or similar devices receiving the necks of the bottles in the manner substantially as indicated in the drawings. I may also and preferably provide a casing 7 forming a chamber receiving the case of bottles and in which the rinsing and sterilizing operations are carried out; the ends of such casing through which the bottle carrying cases may be introduced and removed having movable doors 7^a hinged thereto.

Below the rails for the bottle carrier tubular manifolds indicated at 8 and 9 may be disposed; the manifold 8 having three pipes 10 projecting therefrom, with a series of apertures 11, four in number, through which water and steam, and steam alone, 65 may emerge in the form of jets; while the manifold 9 has four pipes 12 projecting therefrom, with a series of apertures 11, five in number, through which water and steam, and steam alone, 70 may emerge in the form of jets. The jets from the pipes 9 are arranged to register with quart size bottles so that the jets may be properly directed thereto, while the jets from the pipes 11 are arranged to register with the pint size bottles so that the jets may be properly directed thereto. The manifolds may be connected at one end by a U-shaped pipe 13, and at the opposite end by a U-shaped pipe 14; the pipe 13 having a three-way valve 15 whereby the delivery of steam to either manifold may be accomplished, or the steam inlet cut off entirely, while the pipe 14 has a pair of check valves 16 and 17 which are brought into operation when steam is directed into either manifold for passage to the pipes carried thereby having the jetting apertures; such check valves preventing passage of steam to the coil or conduit 2 in the tank or the other manifold. 75 The coil or conduit 2 disposed in the tank for the reception of a charge of water to be discharged into the bottles is provided with a check valve 18 normally open, so 80 that said coil may fill with water during 85 90 95 100 105 110

the intervals in the operation of the apparatus while steam is being jetted into the bottles.

- 5 A pipe 19 leading from the source of steam supply is connected with a pipe 20; one end of which latter pipe is attached to the three-way valve 15, while the opposite end of said pipe 20 is attached to the coil or conduit 2 in the tank. On each side of 10 this connection of the pipe 19 with the pipe 20 is a plunger valve, indicated at 21 and 22, both of which valves may be controlled by a suitable lever 23, so that either one may be opened while the other remains closed. These valves are preferably of the 15 check type and when closed they are held to their seats not only by means of suitable springs but also by reason of the pressure of steam within said pipe 20. They may 20 be raised from their seats against the steam pressure by the arms 24 controlled by the lever 23, upon rocking the latter, such arms engaging heads 25 carried by the stems 26 of said valves.
- 25 If, as illustrated in the diagram, Fig. 4, the valve 21 be opened, steam pressure will enter to force the water from the coil or conduit 2 into the manifolds, thence to the pipes connected thereto, and from the latter 30 in the form of jets; certain of said jets delivering water to the bottles, while other jets rinse the outside of the bottles. The attendant witnessing this operation will discover, following the discharge of the 35 supply of water which has collected in the coil or conduit 2, a vaporous body within the said bottles, being a saturated body of the steam employed to force the water, and as soon as this is apparent the valve 21 40 should be closed and the valve 22 opened, whereby live steam may be delivered through the three-way valve 15 into one of the manifolds 8 or 9, as the case may be, depending upon the position of the said 45 three-way valve, which may be operated by a handle 27. The live steam entering said manifold, passes to the pipes connected thereto and discharges through the apertures of the same in the form of jets into 50 the bottles; one of the check valves in the pipe 14, connected to the opposite end of said manifold preventing escape of the steam through the water line, or to the other manifold. While this is going on, the 55 coil or conduit 2 in the tank is filling with water through the normally open check valve 18, so that when one set of bottles has been pushed away from the rinsing point and the apparatus is ready to receive 60 another set of bottles, there will be sufficient water in said coil or conduit for delivery to the manifolds, and thence to the pipes through which it is jetted to rinse the bottles. The water should be at a temperature 65 of about 150° F., and should have been at

such temperature for some little time, a half hour, for instance, before the rinsing operation commences. It will be seen therefore that the bottles are thoroughly rinsed and raised to a sufficient degree of heat to stand 70 the introduction of live steam to effect sterilization before such steam is admitted thereto.

I have shown separate manifolds with pipes projecting therefrom having apertures 75 to effect a jetting operation of the water and steam, or the steam alone. It will be evident, however, that the manifolds and the pipes may be made in a single casting, and in Figs. 9 and 10, I have shown such arrangement in which 8^a and 9^a represent the manifold portions thereof with a web 10^a between the same, having passages 12^a with jetting apertures 11^a.

It will be understood that the casing 7 85 will catch any excess water or condensed steam and return it to the tank, and that such casing may be provided with a pipe 28 to carry off any excess of vapor present 90 in such chamber during the sterilization operation.

While I have shown valves 21 and 22 controlling the delivery of steam, which valves are arranged to open against the pressure of the steam, it will be understood that such 95 control may be effected by a single three-way valve.

I claim:

1. In bottle rinsing and sterilizing apparatus, the combination of a bottle support; a plurality of jetting devices placed to deliver fluid to bottles carried by said support; a water conduit connected to said jetting devices; a source of steam supply; valves controlling the flow of steam from said source 105 whereby steam may be delivered to the conduit to force water therefrom through said jetting devices and subsequently deliver steam directly to said devices; and means for automatically supplying water to said conduit while steam is being delivered 110 through said jetting devices.

2. In bottle rinsing apparatus, the combination of a bottle support; an apertured pipe placed to deliver fluid to the bottles on the 115 support; a conduit; means for automatically permitting the flow of water into the conduit upon the formation of a vacuum therein; means for delivering steam directly to the apertured pipe or to said conduit to discharge the water therein through said apertured pipe; means for controlling the delivery of such steam, and a check valve placed to prevent the passage of fluid to said conduit from said apertured pipe.

3. In bottle rinsing apparatus, the combination of a bottle support; a plurality of apertured pipes placed to deliver fluid to the bottles on said support; a plurality of manifolds connected to said apertured pipes; a 130

conduit opening to a source of water supply, and connected to the manifolds; a check valve connected to automatically admit water from the source through said conduit under predetermined conditions; means for delivering steam to said conduit to discharge the contents thereof through the apertured pipes; a valve controlling the delivery of such steam through the conduit; means for 10 delivering steam to the manifolds independently of the conduit; and means for preventing the passage of steam from the manifolds to the conduit.

4. The combination of a water containing tank; a jetting device; a conduit submerged in the water of the tank and connected to the jetting device; a source of steam supply connected both to the conduit and to the jetting device; means for automatically admitting water from the tank to the conduit upon the formation of a vacuum in the latter; means for preventing the flow of fluid from the jetting device to the conduit; and means for delivering steam to the pipe or to the 25 jetting device at will.

5. The combination of a water containing tank; a jetting device; a conduit submerged in the water of the tank and connected to the jetting device; a source of steam supply con-

nected both to the conduit and to the jetting device; a check valve connected to the conduit to admit water thereto from the tank; means for preventing the flow of fluid from the jetting device to the conduit; and means for delivering steam to the pipe or to the 30 jetting device at will.

6. The combination in a rinsing and sterilizing apparatus, of a water containing tank; a conduit therein having a check valve placed to permit of flow from the tank; a 40 pair of manifolds, each having a set of apertured discharge pipes; a pipe, including a check valve, connecting each of the manifolds with the conduit in the tank; a steam supply pipe; a valve interposed between the 45 said steam supply pipe and the conduit; means for connecting said steam supply pipe with both of the manifolds; and means for delivering steam into either manifold at will. 50

In testimony whereof, I have signed my name to this specification, in the presence of two subscribing witnesses.

ALFRED G. STEER.
